UNITED STATES PATENT OFFICE.

HENRY V. CONOVER, OF BUFFALO, NEW YORK, ASSIGNOR OF ONE-HALF TO EDWARD H. WOLKIND, OF BUFFALO, NEW YORK.

SEAL FASTENER FOR FREIGHT-CAR DOORS.

Application filed April 24, 1926. Serial No. 104,348.

This invention relates to a seal fastening and is more particularly intended to be used to seal the sliding doors of railroad freight cars in such a manner that an inspection of the 5 lock will give immediate notice of any tampering with the same and enable the officials to promptly institute a search for any goods removed from the car by unauthorized persons, and also by means of periodic 10 inspections, will fix, within certain limits, the place where goods were removed.

One of the objects of this invention is to provide such a seal fastening on which the seal must be shattered and the fragments 15 removed before access may be had to the latching mechanism.

A further object is to provide such a fastening in which the seal is easily inserted before locking the same and in which the 20 latching operation automatically confines the seal.

A still further object is to provide such a fastening in which the fragments from the broken seal fall from the fastening and do 25 not impede the free operation of the same.

In the accompanying drawings:—

Figure 1 is a front view of a portion of the door and body of a freight car showing my seal fastening in its latched position.

Figure 2 is a front elevation of the seal fastening in a partially unlatched position showing the cover plate removed from the casing of the fastening.

Figure 3 is a vertical section taken on line 3—3, Fig. 1.

Figure 4 is a detached rear view of the cover plate.

Figure 5 is a side elevation of the fragile seal disk used to seal the fastening.

In its general organization my seal fastening comprises an apertured casing which houses the latching mechanism and into which the seal is inserted so as to cover the aperture and prevent access to the latching mechanism until the seal is shattered and the fragments removed.

The enclosing casing is relatively flat and rectangular in form and comprises a rear section 6 which is formed to provide the 50 rear, upper, lower and side walls 7, 8, 9 and 10 of the casing and a cover plate 11 which is secured to the front faces of the upper, lower and side walls of the casing by rivets 12 or other suitable fastenings. The rear

section 6 is adapted to be secured to the side 55 of the freight car body B and is provided with integrally formed ears 13 for this purpose which project upwardly and downwardly from the casing and are secured to the side of the freight car by bolts 14.

At its outer sides the enclosing casing is provided with vertical flanges 15 which extend laterally outward from the rear side of the same. The cover plate 11 is larger than the rear section of the enclosing casing and 60 projects outwardly from the margin of the rear section at the upper and vertical sides thereof and thereby forms with the flanges 15 and the upper ear 13, marginal channels 16 which receive the fastening arm 17. The 65 fastening arm 17 is U-shaped and embraces the enclosing casing, and at its outer end is secured to the door D of the freight car. In order to permit the fastening arm to be raised and freed from the casing when it is 70 desired to open the door, the arm is formed at its outer end to provide an elongated bail 18 which is slidably secured to the door by a staple 19.

When the fastening arm 17 is forced 80 downwardly in the side channels 16 of the enclosing casing it is automatically fastened thereto by a beveled latch 20 which is movable into and out of the casing through a recess 21 provided in the side wall thereof 85 and engages a recess 22 provided on the inner side of the fastening arm. This latch is formed integrally with a laterally movable plate 23 which plate is arranged within the casing and at its opposite end is engaged by 90 a flat spring 24 which is secured to the casing by a screw 25 and yieldingly holds said plate and latch in their outer or latching positions.

For the purpose of freeing the fastening arm 17 from the latch 20, the cover plate 11 of the casing is provided centrally with a circular aperture 26 and in rear of this aperture the locking plate 23 is recessed as indicated at 27 whereby the operator can conveniently insert his finger into the enclosing 95 casing and move the latch plate 23 backwardly thereby disengaging the latch 20 from the recess 22 in the fastening arm.

The fastening is sealed by a fragile seal disk 28 which is supported within the casing 100 so as to cover the aperture 26 in the cover and thereby prevent access to the fastening mechanism within the casing. This seal

may be made of any material which is capable of being readily shattered into small fragments by a blow from any convenient instrument, but is preferably made of a disk 5 of wood cut to present the end grain on its front and rear faces and thereby provide a weak and fragile seal. On its opposite flat faces this seal disk preferably has suitable indicia stamped or burned into the same 10 which indicates the name of the railroad and the seal number, or any other record desired. This indicia is readily seen through the aperture in the cover plate when the fastening is being inspected.

15 The seal is held over the aperture 26 in the cover by downwardly converging ribs 29 provided on the inner side of the cover plate on opposite sides of the aperture which engages the periphery of the seal as indicated in Figures 1, 3 and 4, the seal being supported on its front and rear sides by the cover plate and latch plate as indicated in Figure 3. Above these ribs, the upper wall 8 of the casing is recessed to form a relatively large opening 30 through which the seal is inserted into the enclosing casing and falls until engaged by the supporting ribs 29. The lower wall 9 is likewise recessed below the aperture 26 and thereby provides a relatively small opening 31 through which the fragments of the seal drop when it is broken to open the fastening. It will be observed that when the seal is inserted, and the fastening arm forced down and locked to the casing, the upper part of the fastening arm covers the opening 30 and prevents the seal from being removed. The seal is sufficiently loosely arranged in the casing to permit the plate to slide freely and latch the fastening 35 arm to the casing but at all times extends over the aperture 26 and prevents access thereto when intact.

Further protection against opening the fastening by the insertion of a tool and also 45 against the weather is afforded by providing a bead 32 on the front side of the fastening arm which engages the margin of the cover plate and forms a relatively close joint with the same. By this means it is impossible to 50 insert a tool so as to engage the beveled latch 20 and move the same inwardly.

Provision is made for the use of the wire seals now in use should the consignor or consignee require the use of such a seal in addition 55 to the present seal fastening. For this purpose an apertured lug 33 is provided on the casing cover, and the lower end of the fastening arm is provided with an opening 34 which is adapted to register with the 60 opening in the lug 33 and permit the wire of the seal to be passed through the same, the ends being united by the well known lead seal now in use.

As a whole this seal fastening is very simple, durable and inexpensive of construction.

It can be quickly locked and unfastened and reliably operates to prevent opening of the car door without breaking the seal.

I claim as my invention:

1. In a seal fastening, an apertured enclosing casing, a latching mechanism arranged in said enclosing casing and operable through said aperture, a fragile seal, and means for supporting said seal in a position in which it extends across said aperture 70 and prevents access to said latching mechanism, said casing having an opening for the introduction of said seal into said casing, and an opening for the removal of the fragments of said seal when broken.

2. In a seal fastening, an apertured enclosing casing, a latching mechanism arranged in said enclosing casing and operable through said aperture, a fastening member arranged externally of said casing and being adapted to cooperate with said latching mechanism, a fragile seal, and supporting means arranged on the interior of said casing for supporting said seal in a position in which it extends across said aperture and 85 prevents access to said latching mechanism, said casing having a relatively large opening for the introduction of said seal into said casing, and a relatively small opening for the removal of the fragments of said seal 90 when broken, said latching member extending across and closing said first mentioned opening when said seal fastening is in its fastened position.

3. A seal fastening comprising an enclosing casing having an aperture in its front wall, a relatively large opening in its upper side and a relatively small opening in its lower side, a laterally movable plate guided in said casing, a latch secured to said plate 105 and movable into and out of said casing, a spring tending to hold said plate and latch in its outer locking position, a fragile seal adapted to be introduced into said casing through the opening in the upper side thereof, guide ribs arranged on opposite sides of said aperture and adapted to hold said seal over said aperture, and a fastening member adapted to engage and be fastened to said casing by said latch and extend over and 110 close the opening at the upper end of the casing.

4. A seal fastening comprising an apertured enclosing casing, a U-shaped fastening member adapted to engage the opposite 120 sides of said enclosing casing, a latching mechanism arranged in the enclosing casing and having a latch adapted to be moved outwardly into latching engagement with said fastening member, a fragile seal arranged in 125 said casing over said aperture and preventing access to said fastening mechanism and means for introducing and removing said seal from said casing.

5. A seal fastening comprising an enclos- 130

ing casing comprising a rear wall, upper, lower and side walls and an apertured cover plate secured to said upper, lower and side walls, said cover and rear wall extending outwardly from said side and upper walls and forming marginal channels, a vertically movable **U**-shaped fastening member adapted to engage the opposite sides of said casing, said fastening member being arranged within said marginal channels, and having a forwardly projecting bead adapted to engage the margin of the cover plate, a horizontally movable latch plate arranged in said casing, a latch secured to said latch plate and adapted to be moved outwardly from said casing into latching engagement with said locking member, a spring tending to hold said plate and latch in a locking position, and a fragile seal disk, said cover plate having downwardly converging ribs on opposite sides of said seal disk adapted to engage and hold the same over said aperture, and said upper and lower casing walls being recessed to permit the insertion of the seal disk and the removal of the fragments thereof.

25 6. A seal fastening comprising an enclosing casing comprising a rear wall, upper, lower and side walls and an apertured cover plate secured to said upper, lower and side walls, said cover and rear wall extending outwardly from said side and upper walls and forming marginal channels, a vertically movable **U**-shaped fastening member adapted to engage the opposite sides of said casing, said fastening member being arranged within said marginal channels, and having a forwardly projecting bead adapted to engage the margin of the cover plate, a horizontally movable latch plate arranged in said casing, a latch secured to said latch plate and adapted to be moved outwardly from said casing into fastening engagement with said fastening member, a spring tending to hold said plate and latch in a latching position, and a fragile seal disk, said cover plate having downwardly converging ribs on opposite sides of said seal disk adapted to engage and hold the same over said aperture, and said upper and lower casing walls being recessed to permit the insertion of the seal disk and the removal of the fragments thereof.

In testimony whereof I hereby affix my signature.

HENRY V. CONOVER.
